We claim the ornamental design for paper towel dispenser, as shown and described.

DESCRIPTION

FIG. 1 is a perspective view of the towel dispenser.

FIG. 2 is a top view of the towel dispenser.

FIG. 3 is a front view of the towel dispenser.

FIG. 4 is a bottom view of the towel dispenser; and,
FIG. 5 is a left side view of the towel dispenser. The right
side view is a mirror image of the left side view.

The towel dispenser is formed in two halves that are hinged together to form a generally cylindrical container/dispenser for towels. The seam between the halves, the mounting elements, a portion of the exterior, and the serrated edge for tearing-off towels are shown in phantom and are not part of the claimed ornamental design.
